UNITED STATES PATENT OFFICE.

GEORGE F. OISTER, OF CANTON, OHIO, ASSIGNOR OF ONE-HALF TO IRA W. ROYER,
OF CANTON, OHIO.

HUMIDIFIER.

Application filed May 8, 1920. Serial No. 379,733.

To all whom it may concern:

Be it known that I, GEORGE F. OISTER, a citizen of the United States, residing at Canton, in the county of Stark and State of Ohio, have invented a new and useful 5 Humidifier, of which the following is a specification.

This invention relates to improvements in mixing valves and more particularly to a 10 means for injecting moisture into the intake manifold of internal combustion engines.

The objects of the invention are the provision of a mixing valve connected with the 15 water-cooling system of an internal combustion engine arranged to admit moisture to the intake manifold of the engine at a point between the carburetor and the engine.

With these objects in view the invention 20 consists in the novel construction and arrangement of parts, hereinafter described, illustrated in the accompanying drawings, and particularly pointed out in the appended claim, it being understood that various 25 changes in the form, proportions, size and minor details of construction may be made within the scope of the appended claim, without departing from the spirit or sacrificing any of the advantages of the invention. 30

The invention thus set forth in general terms is illustrated in the accompanying drawings forming part hereof, in which—

Figure 1 is a side elevation of an automobile engine showing the application of the improved mixing valve thereto.

Fig. 2 is a gear elevation on an enlarged scale of the mixing valve; and

Fig. 3 is a section on line 3—3, Fig. 2. 40 A practical embodiment of the invention is disclosed in the accompanying drawings, forming a part of this specification in which similar numerals of reference indicate corresponding parts throughout the several views.

An engine casing of any usual and well known design is indicated at 1 provided with the intake manifold 2, the carburetor 3 and the usual pipe 4 leading to the radiator to receive water therefrom in the usual manner, all of these parts being of substantially ordinary form.

The valve comprises the mixing chamber 5 consisting of the cylindrical casing

6 and the cap 7 at the upper end of said 55 casing connected thereto by means of the set screw 8 or its equivalent, a shouldered portion 9 being provided in the lower portion of the casing and forming a seat for the conical air valve 10 which is carried upon 60 the reciprocating valve stem 11 slidably mounted in the bushing 12, which is screw threaded within the cap 7, a coil spring 13 being interposed between said bushing and valve to normally hold the air valve in the 65 closed position as shown in Fig. 3.

A needle valve 14 is provided upon the lower extremity of the valve stem 11 and is arranged to seat within the upper extremity of the angular inlet pipe 15 which inlet pipe 70 extends outward through the side of the casing being carried within the elbow 16 screw threaded within the casing. A needle valve 17 is screw threaded through the outer wall of the elbow 16 and is arranged to seat 75 within the outer extremity of the angular pipe 15. A pipe 18 is connected to the elbow 16 and communicates with the pipe 4 which leads to the radiator.

A stop cock 19 of any usual and well 80 known construction communicates with the upper end of the mixing chamber 5 and with the interior of the inlet manifold, the mixing valve being preferably mounted upon the manifold by means of this stop cock. 85

The suction of the cylinders of the engine will cause the valve stem 11 to be raised against the pressure of the spring 13 opening the air valve 10 and the water valve 14 and drawing atmospheric air together with 90 water into the mixing chamber 5 and this mixture then passes through the stop cock 19 into the intake manifold and thence to the combustion chambers of the engine.

The bushing 12 may be adjusted to regulate the tension upon the spring 13 in order to provide a proper lifting of the valve 10 to admit the proper amount of atmospheric air and the needle valve 17 may be adjusted to admit the desired amount of water.

Although the drawings and above specification disclose the best mode in which I have contemplated embodying my invention I desire to be not limited to the details of such disclosure, for, in the further practical application of my invention, many changes in form and construction may be made, as circumstances require or experience sug-

gests, without departing from the spirit of the invention, within the scope of the appended claim.

I claim:

- 5 In a humidifying device adapted for attachment to an internal combustion engine comprising a cylindrical casing closed at its upper end and open at its lower end to admit air and provided with an outlet in
10 the upper portion, an annular shoulder in the lower end of the cylinder forming a valve seat, a water inlet pipe attachable to the water cooling system of the engine extended into the open end of the cylinder
15 concentric with the valve seat, a valve stem slidably mounted through the upper end of the cylinder and provided with a tapered lower end arranged to normally seat in the end of the water pipe, a hollow conical air valve mounted upon the valve stem, the edge 20 of said conical valve being arranged to normally seat upon the shoulder, and a coil spring encircling said valve stem between the upper closed end of the cylinder and the conical valve to normally close the air and 25 water valves.

In testimony that I claim the above, I have hereunto subscribed my name.

GEORGE F. OISTER.
